INVENTOR.

Louis Charles Reese,

UNITED STATES PATENT OFFICE.

LOUIS CHARLES REESE, OF SAGINAW, MICHIGAN, ASSIGNOR TO WERNER & PFLEIDERER CO., OF SAGINAW, MICHIGAN, A FIRM.

OVEN.

1,171,887.

Specification of Letters Patent. Patented Feb. 15, 1916.

Original application filed April 24, 1915, Serial No. 23,706. Divided and this application filed October 25, 1915. Serial No. 57,736.

To all whom it may concern:

Be it known that I, LOUIS CHARLES REESE, a resident of Saginaw, in the county of Saginaw and State of Michigan, have invented 5 new and useful Improvements in Ovens, of which the following is a specification.

This invention relates to improvements in ovens heated to higher temperatures, such as baking ovens, japanning and enameling 10 stoves, drying kilns, annealing furnaces and the like, and has for its objects greater economy in fuel and labor and greater efficiency in producing and regulating the heat required and in working such ovens than was 15 possible to attain heretofore. To this end I employ a new inverted combustion furnace in which the fuel is burnt by means of air preheated by the waste heat of the oven which may consist of the heat carried away 20 to the chimney by the used fire gases, or of the heat absorbed by the outer structure of the oven and lost to the surroundings. I also introduce air thus preheated into the fire chamber of the oven either in order to 25 burn the combustible gases still contained in the fire gases leaving the furnace, or in order gradually to cool the oven after the furnace has been put out of activity.

The novel features, arrangements, parts 30 and combinations thereof which constitute this invention, are fully explained in the following description of an example of its application which is also represented in the accompanying drawing forming part of this 35 specification.

The drawing represents a longitudinal section of a baking oven heated according to this invention by an inverted combustion furnace similar to that disclosed in an application filed by me on April 24, 1915, and having the Serial No. 23,706, the fire chamber of the oven being situated between the back walls of the furnace and of the baking chamber, and the heat being transferred 40 from the fire chamber to the baking chamber by Perkins tubes.

Like characters of reference indicate corresponding parts serving the same or similar purposes.

50 A represents the oven, B the baking chamber of A, C the Perkins tubes heating B and its contents, D the fire chamber in which the furnace ends of the Perkins tubes are heated

by the fire gases, E the new inverted combustion furnace and F the tube leading air 55 from the front of A into E.

G is the arrangement for heating air taken from the back of the oven and leading it into E, H the channel and distributor conducting the redhot fire gases from E into D, 60 and I the tube and distributor leading air from the front of the oven into D.

The oven A is constructed of brick and iron and completely incloses the back and side walls and a part of the top of the furnace E, the front of the latter being protected against loss of heat by an air-jacket or a mantle of insulating material.

a is the brickwork forming the top of A, and a₁ the flue contained therein and leading 70 the used fire gases from D to the chimney a₂ provided with the slide valve a₃ for regulating the draft.

a₄ is the brickwork between the baking chamber B and the flue a₁, a₅ that forming 75 the front part, and a₆ that of the bottom and foundation of A.

a₇ is the brick work between the back of the baking chamber B and the fire chamber D, and a₈ the brickwork forming the back of 80 the oven inclosing the furnace E.

b is the hearth, b₁ the outer and b₂ the inner door of the baking chamber B.

c, c are the front parts of the Perkins tubes C contained within the baking chamber B and heating same, its contents and the surrounding brickwork a₄, a₅, a₆ and a₇ of A, and c₁, c₂ represent the furnace ends of C absorbing the heat of the fire gases passing through the fire chamber D. The latter has 90 at its upper end the narrow outlet d for the used firegases which, after passing through the wider channel d₁, enter the flue a₁.

The walls of the inverted combustion furnace E consist of the cast iron casing e, the 95 cast iron top e₁ and the firebrick lining e₂. The bottom of E is formed by the grate e₃ which is preferably a so-called rocking grate and self cleaning. The top e₄ carries the door e₅ for charging the furnace with fuel. 100 This door and all the other doors arranged at E and the ashpit belngng to E, must be constructed in such a manner and provided with such appliances that they can be hermetically closed. In regard to the door e₄, 105 this is attained by the movable yoke e₆ strad-

dling e_4 , and the screw e_6 passing through e_5 for tightening the same.

e_7 is a small door arranged immediately above the grate e_3 for stoking the fire in case the grate should refuse to work; e_8 is the movable yoke and screw belonging to this door for tightening it.

e_9 is the channel arranged at the top e_1 for conducting the preheated air from F around 10 e_4 , then through the narrower, but broad channel e_{10} arranged down along the front of the casing e between the channel e_9 and the inlet e_{11} into the burning fuel above the grate.

15 e_{12} is the ashpit belonging to E, but formed by a cast iron structure separate therefrom.

20 e_{13} is the ashpit door which is provided with the tightening arrangement (yoke and screw) e_{14} .

e_{15} is a waterpipe provided with the regulating cock e_{16} for letting water into the incandescent fuel in the furnace if so desired.

25 e_{17} is the insulating material covering the front of the furnace E.

The air pipe F is provided with the graduated slide-valve f for regulating the inflow of air into F and thereby into the furnace E, and f_1 is the coil-shaped part of F placed

130 into the channel d_1 where the used firegases coming fresh from D give off their fiercest heat to the already hot air in F heated in the flue a_1 . For being able to shut off the main-air from the furnace at the back of the oven, F is provided with the throttle valve f_2 worked by the rod f_3 and the handle f_4 .

40 g , g_1 and g_2 are the three compartments of the heating box G in which the air entering the compartment g through the pipe g_3 is preheated by the walls and bottom of the ashpit, the firegas channel H and the surrounding brickwork of the furnace and oven. The air inlet g_3 is provided with the

45 graduated slide valve g_4 for regulating the inflow of air into G. The air entering G through g_3 passes successively through the compartments g , g_1 and g_2 and travels then through the pipe g_5 arranged within the

50 brickwork at the side of the furnace E into the latter, entering at its upper part at g_6 . The tube g_5 is provided with the throttle-valve g_7 worked by the rod g_8 and the handle g_9 .

55 In the arrangement H for conducting the fresh, redhot fire gases from E into D, the latter travel through the opening h the channel h_1 in which light particles of ashes will be retained, and the opening h_2 into D, if the firegases leave the furnace through the grate e_3 ; but, if a special outlet h_3 is arranged above the latter, they pass through h_3 and the channel h_4 into h , and then as before through h_2 into D. The opening h may be blocked in the latter case. Openings

h_5 at the bottom of the channel h_1 which are usually closed by brick blocks, serve for cleaning the channel h_1 .

The air in the tube I is preheated by the spent firegases in the flue a_1 and by the 70 brickwork a_7 receiving the fierce heat of the heating chamber D. I is provided with the graduated slide-valve i regulating the air passing through I, and the distributing channel i_1 with its openings i_2 spreading the 75 air across the length of D.

The *modus operandi* of the furnace E and of its accessories is as follows:—Assuming the fire were to be started, the doors e_4 and

80 e_7 of the furnace, the door e_{13} of its ashpit e_{12} and the slide valve a_2 of the chimney a_2 are widely opened; straw, wood shavings,

cottonwool or the like are then introduced into the furnace E through the door e_4 and lighted. Dry wood is then added, and as soon

85 as the latter burns well, a little fuel, coal, coke, peat or the like, to be used for the work. After this charge has burnt through and is

beginning to become incandescent, the doors e_4 , e_7 and e_{13} are hermetically closed, and the

90 slide valves f and g_4 of the two air inlets of the furnace E are opened. After a short time the first small charge will be aglow and the furnace hot enough; it is then

95 completely filled with fuel through the door e_4 , and, after the latter has been closed again, the heat produced is regulated by regulating the slide valves of the air inlets, f and g_4 .

In this way the foreman who works at the 100 oven front, is enabled to regulate the heat produced and thereby the temperature of the oven without leaving his place.

If the fuel within the furnace is quite incandescent, producer gas may be made by

105 limiting the quantity of air let into the furnace to the required amount, using mainly the air-inlet g_5 . In this case a small amount of water may be introduced into the furnace through the water pipe e_{15} . Air is then

110 introduced into the heating chamber D through the tube I in quantities regulated according to requirements by means of the slide valve i . As soon as air and gas meet in the redhot chamber, the latter lights up

115 immediately without any danger of explosion.

Another object of the airpipe I is to introduce air into D, after the air inlets f and g_4 have been closed and thereby the combustion in the furnace E ceases, in order to cool 120 the fire chamber D and thereby the oven.

I claim:

1. In an oven, the combination with an inverted combustion furnace for heating the same, an oven chamber adapted to receive the articles to be heated, a fire chamber situated between the back walls of the furnace and the oven chamber, a flue running along the top of the oven and leading the 125 spent fire gases from the fire chamber to

the chimney, means arranged at the said flue and worked from the oven front for regulating the draft caused by the chimney in the same, a pipe open to the air and 5 passing along inside the said flue and through the brickwork interposed between the same and the furnace for leading the air thus preheated into the latter, means arranged at the end of the said pipe protruding from the oven front for regulating the amount of air flowing therethrough, a pipe open to the air and passing along inside the flue leading the fire-gases to the chimney and down through the back wall 10 of the oven chamber for leading the air thus preheated to the lower part of the fire chamber, means for distributing the preheated air therein, and means arranged at the end of said pipe protruding from the oven front for regulating the inflow of air 15 thereinto.

2. In an oven the combination with an inverted combustion furnace for heating the same, of an oven chamber adapted to receive the articles to be heated, a fire chamber situated between the back walls of the furnace and the oven chamber and having at the top a narrow passage for the escape of the spent fire gases, means for distributing the burning fire gases coming from the furnace in said fire chamber, a wide channel receiving the spent fire gases from the narrow passage, a flue connecting the said channel with the chimney for leading the spent fire gases thereinto, means for regulating the draft caused by the chimney, a pipe open to the air and running along inside the flue, a coil connected to the said pipe and arranged in the channel situated between the flue and the fire chamber, a pipe connecting the said coil with the furnace, means for regulating the air thus passing into same, a pipe open to the air and running through the flue leading the fire gases to the chimney and down the back wall of the oven chamber, means for regulating the inflow of air into this pipe, means arranged at the said pipe for distributing the air preheated therein in the lower part of the fire chamber, a box arranged underneath the ashpit and the fire chamber for preheating the air therein, means for regulating the inflow of air into the said box, a pipe arranged in the brickwork of the oven for leading the preheated air from the said box to the upper part of the furnace, and means for regulating the amount of air passing through said pipe.

3. In an oven, the combination with an inverted combustion furnace for heating the

same, of an oven chamber adapted to receive the articles to be heated, a fire chamber situated between the back walls of the furnace and the oven chamber, means for distributing the burning fire gases coming from the furnace in said fire chamber, Perkins tubes so arranged as to transfer the heat from the fire chamber to the oven chamber, a flue for leading the spent firegases from the fire chamber to the chimney, means for regulating the draft in the said flue, a pipe open to the air and passing through the said flue for leading the air thus preheated to the furnace, means for regulating the amount of air passing through the said pipe, a pipe open to the air and passing through the back wall of the oven chamber for leading the air thus preheated to the lower part of the fire chamber and means for regulating the amount of air passing through this pipe.

4. A baking oven heated by Perkins tubes, comprising a baking chamber, a double door for working the same, an inverted combustion furnace, a fire chamber in which the furnace ends of the Perkins tubes are heated, and which is situated between the back walls of the furnace and of the baking chamber, means for distributing the burning fire gases coming from the furnace in said fire chamber, a flue leading the spent fire gases from the fire chamber to the chimney, means for regulating the draft in this flue, a pipe open to the air passing through the said flue for leading the air thus preheated into the furnace, and means for regulating the amount of air passing through this pipe.

5. A baking oven heated by Perkins tubes, comprising an inverted combustion furnace, a baking chamber, a fire chamber in which the furnace ends of the Perkins tubes are heated, and which is arranged between the furnace and the baking chamber, ducts leading the fresh fire gases from the furnace to the fire chamber and adapted to retain the ashes contained in the fire gases, a pipe open to the air and arranged within the brick-work of the oven for leading the air thus preheated into the furnace, means for regulating the air passing through the said pipe, a pipe open to the air arranged within the back wall of the oven chamber leading the air thus preheated to the lower part of the fire chamber and means for controlling the air passing through the said pipe.
